DUAL ACTION MAGNETIC RELAY WITH VARIABLE AIR GAP

Filed Dec. 29, 1950

UNITED STATES PATENT OFFICE

2,636,934

DUAL ACTION MAGNETIC RELAY WITH
VARIABLE AIR GAP

Thomas G. A. Sillers, Wauwatosa, Wis., assignor
to Allis-Chalmers Manufacturing Company,
Milwaukee, Wis.

Application December 29, 1950, Serial No. 203,294

3 Claims. (Cl. 175—372)

1

This invention relates to improvements in automatic circuit protective devices and more particularly to a new and improved delayed action overcurrent electromagnetic relay.

The usual type of electromagnetic relay has a characteristic fast action which is not adapted to certain circuit arrangements, such as are involved in switchgear circuit breaker practice. This type of application requires a relay with a time delayed action. The period of time during which electric equipment can be subjected to abnormal conditions, such as high currents or short circuit currents, is ordinarily variable depending upon the character or intensity of such abnormal conditions. In some cases it is desirable to permit the electric system to remain intact for a period of time that varies with the value of an abnormal condition. At high values of overload currents or short circuit currents, it is desirable that the circuit be interrupted after a time interval which is comparatively small but which, nevertheless, insures freedom from interruption due to momentary disturbances.

Power distribution systems are frequently protected by a number of serially connected circuit breakers which operate in a predetermined sequence. Each serially connected breaker is adjusted to trip at a different predetermined interval of time, thereby sequentially isolating segments of the electric circuit in accordance with the location of the disturbance, the length of time the disturbance continues, or the character of the disturbance. Heretofore, time delay relays have been used to sequentially trip serially connected circuit breakers but these relays have not been capable of accurate settings for such short time intervals as are desirable for clearing circuit faults with a minimum of burning of connections and connected apparatus.

In accordance with the invention claimed, a new and improved delayed action overcurrent electromagnetic relay is provided for circuit breaker operation which has a given current-time characteristic for currents up to a predetermined value and a different current-time characteristic for currents above that predetermined value.

In the preferred embodiment of the invention, the magnetic relay embodies an armature which actuates a switch operating rod. The rod is retarded by a pair of suction disks from moving into switch actuating position in a time varying inversely of the current traversing the winding of the relay. For currents below a predetermined value the armature is disposed adjacent the relay

2

core structure to provide an air gap of a predetermined size, and for currents above a certain value the armature is actuated to another position to provide a smaller air gap. In the armature's second position, the flux induced in the iron core structure is greater than it would have been had the air gap retained the length it had in the armature's first position, and consequently, the inverse time characteristic has been changed to permit the time delay relay to operate in a shorter time for currents above the predetermined value.

It is, therefore, one object of the present invention to provide a delayed action overcurrent electromagnetic relay in which the relay has a given current-time characteristic for overload currents up to a predetermined value and a different current-time characteristic for currents above that predetermined value.

Another object of this invention is to provide a delayed action magnetic relay with dual inverse time relationships which provide for adjustments of the point of changeover from one relationship to the other.

25 A further object of this invention is to provide a new and improved delayed action relay which is adjustable for operation at predetermined current values with predetermined periods of time delay.

Objects and advantages other than those set forth will be apparent from the following description when read in connection with the accompanying drawing in which:

30 Fig. 1 is a diagrammatic view of a circuit breaker and a delayed action overcurrent electromagnetic relay therefor embodying the present invention; and

35 Fig. 2 is a graph of the current-time characteristics of the electromagnetic relay illustrated in Fig. 1 and a graph of current-time characteristics of a prior art circuit breaker tripping device.

40 Referring more particularly to the drawing by characters of reference, Fig. 1 illustrates an electric circuit 6 provided with a circuit interrupter or breaker 7 and a time delay overcurrent electromagnetic relay 8 for controlling its actuation at predetermined overloads. The relay comprises a magnetizing winding 9 connected to one phase conductor of the electric circuit 6. Winding 9 may be connected in series with the associated phase conductor, or may be connected therewith through a current transformer, as is well known. The relay further comprises a core structure 10 and an armature 11. Armature 11 is

of cylindrical form and is provided with a central opening 12 adapted to be closed at one end thereof by a nut 13. A threaded core 14 extending through the central portion of the nut and within the armature 11 is coaxially aligned with the armature to form a part thereof. The armature is disposed adjacent core structure 10 to form therewith a magnetic circuit having a given air gap.

The armature 11, nut 13 and core 14 are provided with aligned openings loosely receiving a rod 15 adapted to actuate the circuit breaker switch arm 18. The rod 15 is provided with a flange portion 19 adapted to fit loosely within armature 11 and to close the upper end of armature 11 when the relay is in the position illustrated in Fig. 1. The lower end of the rod 15 is threaded into a nut 20 which is, in turn, suitably secured to one of a pair of suction disks. Nut 20 may be pinned to rod 15 to lock it in place, if so desired. A resilient means such as a spring 16 is arranged within armature 11 about rod 15 for opposing movement of armature 11 relative to rod 15.

A rigid cylinder 22 surrounds the lower end of armature 11 and is suitably secured to core structure 10 and acts as a guiding means or bearing for the armature. Flange 19 of rod 15 acts as a guiding means for the upper end of armature 11 and a rigid cylinder 23 suitably secured to core structure 10 acts as a guiding means or bearing for the upper portion of rod 15.

The suction disks are arranged in an oil bath with the upper disk 24 secured to rod 15 and the lower disk 25 secured to the bottom of a container 26 which houses the oil.

Circuit breaker 7 as illustrated in the drawing comprises stationary arcing contact 29 and movable arcing contacts 30. The movable arcing contacts 30 are connected to a rod 31 which is actuated to circuit open position by a toggle mechanism 32.

The toggle mechanism 32 comprises a link 33 which is pivotally mounted at 34 and a link 35 which is pivotally mounted at a point 36 on rod 31. A spring 37 biases toggle mechanism 32 to circuit open position. Link 33 carries a lug 38 which is engaged by a catch 39. Catch 39 is mounted on one end of pivotally mounted lever arm 18 and is held in its operative position against a stop 40 by means of a spring 41. Lever arm 18 is actuated by rod 15 when it is actuated to switch opening position by armature 11.

In Fig. 2 curve ABC illustrates a time-current curve of the usual prior art current responsive relay. The curves ABD, A'EG, and A''FH illustrate the time-current curves of the electromagnetic relay illustrated in Fig. 1 with different adjustments. These curves are plotted, having as abscissa current and having as ordinate time. All of the curves are plotted on the basis of the relay being set for tripping only on values of current above 100% load. Fig. 2 illustrates diagrammatically the manner in which the device shown in Fig. 1 operates and is not intended to set any limits within which this invention must be restricted.

In operation, the circuit breaker 7 being closed as indicated in Fig. 1, current flows through the arcing contacts 29, 30 and the magnetizing winding 9. For all line currents below a predetermined value the parts of the relay remain in the position indicated. Upon the occurrence of a line current through magnetizing winding 9 of a certain overload value below a predetermined

value, armature 11 after a predetermined delay moves rod 15 and actuates arm 18 to trip the circuit breaker 7.

Operation of the relay illustrated in Fig. 1 for overload currents below a predetermined value may be illustrated by curve ABC, shown in Fig. 2. This type of inverse time delay is characteristic of the prior art relay structures wherein the time delay is inversely proportional to the current flowing through the magnetizing winding for the full overload current range of the relay.

In order to permit the relay to operate faster for overload currents above a predetermined value the relay illustrated in Fig. 1 is provided with an armature which is capable of moving relative to the switch actuating rod 15 from a first position to a second position. In the second position of armature 11, the air gap between the armature and the upper part of the core structure is smaller and the magnetizing flux introduced in the core structure is greater per unit of current flowing through the magnetizing winding than it would have been if the armature remained in its first position. Consequently, the inverse time relation between switch actuation and the value of the current flowing through the magnetizing winding has been changed.

The inverse time relation for a given relay setting for currents above a predetermined overload value is represented by curve BD. Therefore, the relay illustrated in Fig. 1 operates for all overload currents below a predetermined value on the curve AB and for all overload currents above a predetermined value on the curve BD. The difference of ordinates between curves BC and BD for any given overload current is representative of the time gained in tripping the circuit breaker by use of this invention in preference to the prior art structures represented by curve ABC.

The actual mechanical operation of the relay illustrated in Fig. 1 is as follows:

For all overload currents below a predetermined current value represented by the point B on the curve ABC, at a given setting, the current flowing through the magnetizing winding 9 will introduce a magnetizing flux in core structure 10 which will attract armature 11 in switch actuating direction. Armature 11 is opposed from moving by the spring means 16 which bears against flange 19 and nut 13 and the suction disks 24 and 25. The thrust exerted by armature 11 on rod 15 through spring 16 depends on the value of the current in coil 9. After a predetermined period of time, this thrust causes the suction disks to separate, and the armature 11 will actuate rod 15 into position to trip the circuit breaker 7.

For all overload currents above the predetermined value represented by point B on the curves illustrated in Fig. 2, armature 11 will be actuated by the magnetizing current flowing through winding 9 to move upward relative to rod 15 toward the upper part of core structure 10 against the opposing force of spring 16. The movement of armature 11 is stopped temporarily when the upper portion of core 10 strikes against flange 19 of rod 15 to interlock the armature and the rod for movement as a unit. In so moving from its original position to the position where core 10 strikes flange 19 of rod 15, armature 11 has decreased the size of the air gap between the armature 11 and the core structure 10. The magnetizing flux now introduced in the core structure 10 for the same overload current which actu-

ated armature 11 to its second position is stronger than it was when the armature was in its original or first position. Consequently, now the movement of rod 15 toward lever 18 against the biasing force of the suction disks 24 and 25 will vary in a new inverse time relationship represented by curve BD.

Thus, the relay illustrated in Fig. 1 has a certain time delay for overload currents below a predetermined value and a much smaller time delay for overload currents over this predetermined value. For exceptionally high overload current, the relay operates almost instantaneously.

The electromagnetic relay 8 may be adjusted so that it may have a number of inverse time ratios for currents above any predetermined overload current. In this manner the same type of relay may be used to protect any number of serially connected circuit breakers which are arranged to operate in a predetermined sequence. Each relay is adjusted to trip at a different predetermined interval of time.

This adjustment is accomplished by screwing armature 11 up or down in the threaded core 14. By moving armature 11 toward flange 19, the air gap when armature 11 is in its second position is reduced and the breaker will be tripped in a shorter time interval than it would have been formerly. Movement of armature 11 away from flange 19 increases the air gap when the armature is in its second position and thereby increases the time delay for a predetermined overload current. Adjustment of the tension on spring 16 also may be provided for further variations of the time current characteristics.

Curves A'EG and A''FH represent the inverse time relation of relay 8 for two representative settings of the relay wherein the armature 11 was moved to increase the air gap for the armature in its second position.

Thus, a plurality of relays of the type illustrated may be adjusted to trip at different predetermined intervals of time, thereby sequentially causing isolation of faulty circuits.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. A time delay relay comprising a core structure, an armature disposed adjacent said core to form therewith a magnetic circuit having a given air gap, a magnetizing winding for producing a magnetic flux in said magnetic circuit, a rod to be actuated by said armature, means for retarding the movement of said rod in a time varying inversely of the value of the current traversing said winding, resilient means acting between said armature and said rod for opposing movement of said armature relative to said rod,

said armature moving relative to said rod from a first position to a second position when the current traversing said winding reaches a predetermined value, said movement of said armature relative to said rod varying said air gap to vary the inverse time relation between rod movement and the value of said current, and means for interlocking said armature and said rod in said second position for further movement as a unit.

2. A time delay relay comprising a core structure, an armature disposed adjacent said core to form therewith a magnetic circuit having a given air gap, a magnetizing winding for producing a magnetic flux in said magnetic circuit, a rod extending through said armature and operated thereby, means for retarding the movement of said rod in a time varying inversely of the value of the current traversing said winding, resilient means within said armature about said rod and acting between said armature and said rod for opposing movement of said armature relative to said rod, said armature moving relative to said rod from a first position to a second position when the current traversing said winding reaches a predetermined value, said movement of said armature relative to said rod varying said air gap to vary the inverse time relation between rod movement and the value of said current, and cylindrical means around said rod and within said resilient means for interlocking said armature and said rod in said second position for further movement together as a unit.

3. A time delay relay comprising a core structure, an armature disposed adjacent said core to form therewith a magnetic circuit having a given air gap, a magnetizing winding for producing a magnetic flux in said magnetic circuit, a rod to be actuated by said armature, means for retarding the movement of said rod in a time varying inversely of the value of the current traversing said winding, resilient means acting between said armature and said rod for opposing movement of said armature relative to said rod, said armature moving relatively to said rod from a first position to a second position when the current traversing said winding reaches a predetermined value, thereby reducing the size of said air gap to vary the inverse time relation between rod movement and the value of said current, and a flange secured to said rod for interlocking said armature and said rod in said second position for further movement as a unit in gap closing direction.

THOMAS G. A. SILLERS.
